[57] CLAIM

The ornamental design for a portfolio having internal compartments as shown and described.

DESCRIPTION

FIG. 1 is a left, front perspective view of a portfolio having internal compartments showing my new design; FIG. 2 is a perspective view thereof, with the portfolio in open condition, the broken lines are for illustrative purposes only and form no part of the claimed design; FIG. 3 is a left side elevation view thereof with the portfolio in closed condition;

FIG. 4 is a right side elevation view thereof with the portfolio in closed condition;

FIG. 5 is a top plan view thereof in closed position; and, FIG. 6 is a bottom plan view thereof in closed position.
